FRANCIS MARION WATKINS AND RAY CUNNINGHAM, OF REWARD, CALIFORNIA.

BEARING ADJUSTER.

Application filed September 20, 1926. Serial No. 136,610.

It is the purpose of this invention to provide a novel construction of means for tightening and keeping in adjustment, the wrist pin bearing block of the character used on all standard pumping and drilling apparatus used in oil fields and the like.

In carrying out the invention I contemplate a structure which can be used with either wooden or metallic bearing blocks, and also provide for the supporting of the bearing block within the pitman when the latter is removed from the wrist pin on the crank band wheel shaft of the apparatus.

The nature and advantages of the invention will be better understood when the following detail description is read in connection with the accompanying drawings, the invention residing in the construction, combination and arrangement of parts as claimed.

In the drawings forming part of this application like numerals of reference indicate similar parts in the several views and wherein:

25 Figure 1 is a view in elevation showing one embodiment of the invention.

Figure 2 is a vertical sectional view therethrough.

30 Figure 3 is a perspective view of the follower.

Referring to the drawings in detail and more particularly Figures 1 to 3 inclusive, 10 represents a pitman which is slotted to accommodate the bearing blocks for the

35 wrist pin 11. The lower block of the bearing indicated at 12 is stationary, while the upper block 13 is susceptible of adjustment so that it may be tightened from time to time as the occasion may require, and held

40 fixed relatively to the block 13 in any given position. As shown in these figures, the bearing blocks are constructed of metal, although it is desired to be understood that said blocks may be formed from any ma-

45 terial without departing from the spirit of the invention. The block 13 varies from the block of usual construction, in that it is channeled as at 14 and provided with a slot along the upper edge thereof to accommodate

50 the form of follower indicated at 15 in Figure 3. A metallic bearing plate 16 straddles the upper edge of the slot in the pitman 10 as illustrated, and the upper edge of the follower is beveled or inclined as at 17 to ride or bear against the plate 16, which is

arranged at an angle as illustrated. The follower is formed with a substantially T-shaped extension 18 which is received by a correspondingly shaped slot 18 formed in the adjacent end of the block 13, with the 60 head of the extension arranged within the channel portion 14 as clearly illustrated in Figure 2. The follower is provided with a threaded bore 19 which receives an adjusting screw 20 which is journaled in the pitman 10 and provided with a crank handle 21, through the instrumentality of which the screw is rotated. The initial position of the follower 15 is illustrated in Figure 1, and when it is desired to tighten the bearing 70 block 13 it is only necessary to rotate the screw 20, to feed the follower along the screw, the inclined face 17 thereof riding against the lower edge of the angular bearing plate 16 causes the block 13 to be lowered and tightened as will be readily understood. In this manner the bearing can be quickly and conveniently adjusted, and the block 13 held fixed with relation to the block 12 in any given position. By reversing the rotation of the screw 20, the follower is moved in an opposite direction, which of course loosens the bearing block 13 to permit the pitman to be separated from the crank pin 11, and by reason of the 80 construction of the follower 15, and its association with the bearing block 13, the latter is supported within the opening of the pitman after the latter has been removed from the crank pin. 85

90 While it is believed that from the foregoing description, the nature and advantages of the invention will be readily apparent, we desire to have it understood, that we do not limit ourselves to what is 95 herein shown and described and that such changes may be resorted to when desired as fall within the scope of what is claimed.

What is claimed is:

A wrist pin bearing comprising in combination with a support and bearing blocks mounted therein, one of said blocks having an opening adjacent its upper end and having its upper surface provided with a slot communicating with said opening, an adjusting screw journaled on said support above said block, a follower mounted on said screw and including a substantially inverted T-shaped extension the stem of which is adapted to pass through said slot, to support 110

the block within the support when the latter is removed from the wrist pin the head of said extension being arranged in said opening with the top wall of the bearing block arranged between the follower and said head, an inclined bearing plate, and said follower having a beveled surface cooperat-

ing with said plate whereupon adjustment of said block is effected upon movement of the follower in one direction.

In testimony whereof we affix our signatures.

FRANCIS MARION WATKINS.
RAY CUNNINGHAM.
